UNITED STATES PATENT OFFICE

2,434,924

FLAME FAILURE CONTROL APPARATUS

James C. Hamilton, Lexington, Mass., assignor
to Combustion Control Corporation, Cambridge,
Mass., a corporation of Massachusetts

Application June 20, 1945, Serial No. 600,535

9 Claims. (Cl. 250—41.5)

1

This invention relates to electronic control apparatus of the photoelectric type as applied to boilers, furnaces and the like in use in numerous commercial, industrial, marine and other installations where protection against explosion and other damage caused by flame failure is of vital importance. More particularly, this invention relates to intermediate mechanical apparatus located between the electronic control apparatus proper and a boiler or furnace interior for the purpose of controlling the light admitted to a photoelectric cell or other light-sensitive member from the flame of the burning fuel and protecting the entire control from heat.

It is a well-known fact that flame failure in oil burners and other types of flame-heated furnaces, boilers and heaters not only disrupts production schedules in industrial plants but often cause very damaging explosions resulting in serious fires and in many instances in heavy loss of life.

One of the chief difficulties in providing a safety device of the photoelectric type for flame-heated furnaces is in obtaining adequate protection of the photoelectric cell and other parts comprising the electronic control system against excessive heat.

In the past, due to the fact that light from the flame inside of the furnace must be admitted to the photoelectric cell and that in many furnace installations space is very limited, it has been necessary to mount the photoelectric cell very close to the furnace and to separate the photocell from the rest of the electrical apparatus which is generally remotely located on a wall of the furnace room. In this case it is usually necessary to connect the photocell to the control apparatus by shielded or coaxial cable.

One of the factors responsible for producing excessive heat is the absorption of infrared radiation by the filter used to prevent this frequency of radiation from reaching the light-sensitive device. This filter is usually composed of a heat-absorbing type of glass. In the past, this filter has been either fixed in a wall of the container enclosing the photoelectric cell or otherwise closely associated with the container in such a manner as to allow considerable conduction of the absorbed heat to the photoelectric cell.

The present invention obviates these difficulties by providing novel intermediate insulating apparatus in combination with the container enclosing the photoelectric cell. Means are provided for removal by convection and radiation not only of conducted heat from the furnace but of the radiated heat absorbed by the infrared fil-

2

ter and for separation of the filter from the container so that a minimum of heat reaches the photoelectric cell. Because of these improvements it is now possible to enclose the whole electronic circuit with its component parts in the same container with the photoelectric cell with a resultant shortening of connections between the photoelectric cell and the rest of the electronic circuit, and elimination of the extra housing and labor of installation. At the same time it is possible to mount the whole apparatus as close to the side wall of the furnace as necessary to permit direct viewing of the flame by the photoelectric cell. Recapitulating the above features,

15 The principal object of this invention is to provide an improved apparatus in which is housed a complete photoelectric flame-failure control system directly connected to the wall of a furnace;

Another object is to provide apparatus of the 20 type above identified in which a heat-absorbing filter is separated from a container in which is located the photoelectric cell and component parts of the electronic control system;

A still further object in the said apparatus is 25 to provide means connecting said housing with the furnace which permits free circulation of air between the furnace and photoelectric cell container resulting in a substantial lowering of the temperature in said container;

30 Still another object in said apparatus is to provide for quick and easy cleaning of the several windows or filters incorporated in said apparatus without the use of tools;

Still further objects in this invention are 35 prevention of condensation of moisture on the windows or filters when the apparatus is subjected to extreme humidity; automatic prevention of soot or dust deposit on the glass exposed to the interior of the furnace and prevention of dust collection on the surfaces of the glasses on the outside of the furnace; provision for readily attaching additional radiation plates as found desirable under conditions of excessive heat. Other objects and novel features will be apparent from 40 the following description of the operation and construction.

Referring more in detail to the drawings:

Fig. 1 is a partial side elevation and vertical cross-section, portions of which are broken off for 45 convenience and other portions of which are shown diagrammatically;

Fig. 2 is a plan view of the principal part of the apparatus, portions of which are broken off for convenience;

55 Fig. 3 is a partial vertical cross-section and

elevation taken on the line 3-3 of Fig. 2, portions of which are broken away to better show details of the more important elements;

Fig. 4 is an end elevation of the main apparatus as viewed from the furnace end, the pipe member being removed;

Fig. 5 is a vertical cross-section taken on the line 5-5 of Fig. 2, one of the pivoted elements of which is shown in its open position, as indicated by the dot-and-dash lines;

Fig. 6 is a vertical cross-section taken on the line 6-6 of Fig. 2, one of the pivoted elements of which is shown in its open position, as indicated by the dot-and-dash lines;

Fig. 7 is a fragmentary cross-section taken on the line 7-7 of Fig. 2 showing the method of bolting the various elements of the device together;

Fig. 8 is a fragmentary cross-section taken on the line 8-8 of Fig. 4 showing the means for locking the plain glass holder against premature or accidental movement;

Fig. 9 is a fragmentary cross-section taken on the line 9-9 of Fig. 4 showing the means for locking the infrared filter holder against premature or accidental movement;

Fig. 10 is an enlarged fragmentary cross-section and elevation, portions of which are broken away for convenience, showing the apparatus as used without insulating collars between certain of the radiation plates; and

Fig. 11 is a partial fragmentary cross-section and elevation, portions of which are broken away for convenience and particularly for showing a modification of the radiation plates.

Inasmuch as the present invention and application is not directly concerned with the operation of the electronic circuit used with the photoelectric cell, the function of which is well known in the art, detailed description will be limited to reference to the photoelectric cell only and its container together with connecting apparatus intermediate the furnace. It is to be understood that this apparatus may be useful wherever it is desired for any reason, to admit light to a container and at the same time protect the contents from excessive heat.

Referring more in detail to the drawing, 15 indicates a container body and 16 indicates a removable cover which may be attached to the container in an air-tight manner by use of a suitable gasket if desired. Within the container body 15 is located a conventional photoelectric cell 17, the cathode element of which is exposed to a sight opening 18 provided in the front end of the container body 15. A piece of plain glass or other transparent medium 19 is sealed in a moisture-proof manner in a recess located on the inside of the container body 15 around the sight opening 18. Any convenient fastening means for securing the transparent member 19, as the fasteners 20 and screws 21, may be used.

At 22 is located a pipe flange which is provided with bosses 23 located at its four corners. The bosses 23 are counterbored to receive the socket heads of bolts 24, the threaded ends of which pass through holes in the container body 15 and terminate inside of said container. If preferred, the threaded ends of bolts 24 may be secured in threaded bosses located on the exterior of the container 15. Between the flange 22 and the front end of the container body 15 are spaced a plurality of relatively thin plates 25, 26, 27 and 28. These plates are maintained in spaced relationship between the flange 22 and the container body 15 by means of spacing sleeves 29 herein-

after referred to as spacers. The bolts 24 pass through the plates 25, 26, 27 and 28 and the spacers 29 and are tightened up inside of the container body 15 by means of the nuts 30, thereby forming a rigid assembly between the flange 22 and the container body 15. Plates 25, 26, 27 and 28 are each provided with a central orifice 31, the edges of which are rolled over to form narrow flanges as indicated at 32. The flanges 31 of the plates 26 and 27 face each other while the flange 31 of plate 28 faces the end of the container body 15 which is provided with a bead 33 around the sight hole 18. Between the plates 26 and 27 and plate 28 and container body 15 are positioned insulating collars 34, the inside diameters of which are greater than the outside diameters of the flanges 32 on the plates and the bead 33 on the container body 15 so that at no time can the collars 34 move away from the outside diameter of the said flanges 31. Plate 25 is similar to the other plates 26, 27 and 28 excepting the orifice 35 which is slightly larger and has no rolled edge. If preferred, the orifice 35 of plate 25 may be the same as the orifice 31 in plates 26, 27 and 28. In such cases the rolled edge should extend toward the threaded boss of the flange 22.

Located between plate 25 and plate 26 is a shutter member 36. This shutter 36 is provided with a boss 37, see Fig. 3, which is journaled at 38 around one of the top spacers 29. On the lower end of shutter 36 projects an extension finger 39 for the purpose of providing a finger grip for the operator to swing the shutter outwardly from the plates 25 and 26. A friction spring clip 40 is attached to the inside face of the extension finger 39. When the shutter is closed, the clip 40 engages over the spacers 29, as shown in Fig. 5, normally holding said shutter in a closed position. The shutter 36 is also provided with an orifice as indicated at 41 which is in axial alignment and concentric relationship with respect to the openings in the pipe boss of flange 22, plates 25, 26, 27, 28 and sight opening 18 in the container body 15. On the side of the shutter 36 facing the container body 15 is located a recess 42 also concentrically located with respect to the orifices in the other members in which is fastened by means of a snap ring 43 a plain heat-resistant sight glass or other transparent medium 44. On the side of the shutter 36 adjacent the plate 25 are located two rivet members 45, the flat heads of which bear against the side of the plate 25 and maintain the shutter away from one side of the plate 25, as shown in Fig. 3. An air space 46 is thus provided between the plate 25 and shutter 36, the reason for which will be explained further along in the description.

Between the plates 27 and 28 is located a second shutter 47. This shutter is identical with shutter 36 with one exception: the rivets 45 of shutter 26 are eliminated. A clip member 40a attached to the finger 39a is provided as in shutter 36 and engages over a corresponding spacer 29. In order to provide a close contact of the shutter 47 with the plates 27 and 28, the spacers 29 in this section are slightly shorter than those in the section occupied by the shutter 36 to the extent of the approximate width of the air space 46, working tolerances excepted. As noted in the drawings, shutter 47 is mounted in an opposite manner to shutter 36 so that it swings outwardly from the other side of the assembly.

Located in the recess 42a of shutter 47 is an infrared filter member 48 held in place by another

snap ring 43a in like manner, as in shutter 36. Shutter 47 is provided with a boss 38a journalled around one of the spacers 29 in a similar manner as in shutter 36.

Threaded in the boss of the flange 22 is a pipe 49, the other end of which engages through the side wall of the fire box of a furnace 50. The pipe 49 may be welded or connected by other means to the furnace wall in which a hole of suitable size has been cut. The pipe is attached to the furnace wall in such a position that its axis passes without obstruction through some part, preferably the hottest part, of the flame 51 inside the fire box.

By an inspection of Figs. 1 and 3, it will be noted that the horizontal axes of the openings of the pipe 49, flange 22, plates 25, 26, 27, 28 and sight opening 18 in the container body 15 coincide, so that light from the flame is admitted to the cathode of the photoelectric cell 17. Failure of the flame 51 with the resultant change in the light falling on the photocell will immediately cause electrical changes in the electronic circuits designed to control fuel feed lines to the burner, such electronic control means being well known in the art.

In operation, the shutters 36 and 47 are closed, as shown in Fig. 3 of the drawings. In the closed position of shutter 36 it will be noted that between the plate 25 and the shutter there is present an air space previously referred to and indicated by the numeral 46. It will be noted by an inspection of Fig. 3 that this air space 46 is positioned on the fire box side of the transparent member 44. Since, in most furnaces, the pressure inside the fire box is somewhat lower than atmospheric pressure because of the chimney draft, a small amount of air will be drawn into the pipe 49. In the present device the current of air through the space 46 tends to cool the member 44 and also reduces to a minimum the deposit of soot on the member so that the necessity for frequent cleaning, with the attendant possibility of breakage, is eliminated. Whenever it becomes necessary to clean the transparent member 44, the shutter 36 may be swung by use of the finger grip 39 and both sides of the member 44 may be wiped off clean. When the shutter is again closed, the spring clip 40 engages over the spacer 29, holding the shutter securely in place as shown in Fig. 5.

In a similar manner the shutter 47 carrying the infrared filter 48 may be swung out and the filter cleaned of any dust particles which may have collected on it. The arrangement of the shutters on opposite sides of the apparatus makes the possibility of their both being opened simultaneously unlikely so that the chance of a momentary blow-back of the furnace causing a deposit of soot on glass 19 is extremely remote.

As heretofore mentioned in the objectives of this invention, due to the novel construction of this apparatus the infrared filter is mounted outside of the casing enclosing the photoelectric cell and electrical circuits, etc. and such a filter may, if desired, be spaced still further away from said casing by the simple expedient of adding more plates and spacers between plate 28 and the casing. In some installations the temperature of the boiler wall may be very high and additional plates and spacers may also be required between the filter and the mounting flange. Where it is desired to add more plates either between plates 26 and 27 or plate 28 and casing 15 no change in construction is necessary except for the use of correspondingly longer

bolts 24. Due to the fact that the plates 25, 26, 27 and 28 are always at a higher temperature than the surrounding air and the fact that open spacing is present between the plates, there is an induced circulation of air up through these openings resulting in efficient removal of the heat acquired by these plates by conduction through the mounting flange from the furnace wall and by contact with the heat-absorbing filter 48.

The insulating collars 34 are mainly provided for use under very dusty conditions for the purpose of reducing dust accumulation on the transparent members 44 and 48; however, under extremely humid atmospheric conditions, as in tropical climates, the collars 34 may be dispensed with, thereby reducing the possibility of moisture condensation on the transparent members when the furnace is not in use.

As previously set forth, the present invention may be applied to marine installations and other portable heating or power installations.

As an illustration, it may be assumed that the installed equipment is on a ship's boiler. In such case it will be apparent that the apparatus may be subjected to sudden shocks and jars which under the right conditions might cause the shutters 36 and 47 to be snapped out of position. To provide against premature or accidental opening of the shutters 36 and 47, a locking member has been provided as shown in the fragmentary cross-sections shown in Figs. 8 and 9. Referring more in detail to Fig. 8 it will be noted that the flange 22 has been provided with an extension portion 60, the inner surface of which is counterbored at 61 and threaded at 62, the threaded portion 62 being slightly smaller in diameter. The shutter 36 is provided with a threaded hole 63 at a point in axial alignment with the threaded opening 62 on the flange 22 when the shutter 36 is in a closed position, as in Figs. 4 and 5. Axially aligned in the openings 62 and 63 is a captive screw comprising a knurled extension end 64, shank 65, and enlarged threaded plug end 66.

When it is desired to lock the shutter 36 in place, the plug end 66 may be threaded through the hole 62 and then pushed through counterbored recess 61 and an enlarged hole 67 located in plate 25, after which the plug 66 is threaded into the hole 63 in the shutter 36 and tightened up against the flange 22.

To open the shutter 36, the plug 66 of the captive screw is unscrewed from the threaded hole 63 in the shutter and withdrawn into the counterbored area 61 of the flange 22 and the shutter 36 may be swung out as previously described. Due to the fact that the hole 62 is provided with a thread of the same diameter as the plug end 66, the captive screw will not fall out and requires further unscrewing to remove it from the assembly, thereby preventing loss or mislaying of said screw.

In a similar manner, a captive screw may be provided on the other side of the apparatus to lock the shutter 47 as shown in Fig. 9. For the sake of simplicity, similar numerals, as 60a to 67a, have been used in Fig. 9, the locking and unlocking action being identical in either instance.

In stationary installations where the apparatus is not likely to be subjected to sudden shocks, etc., the captive screws may be removed entirely or they may be left in an unlocked position as desired.

Also under certain conditions where it is not

desirable to admit any air to the furnace except through the burner, the rivets 45 in the shutter 36 may be eliminated so that the shutter and plate 25 effect a seal when the shutter is closed similar to shutter 47 and plates 27 and 28, better shown in Fig. 10.

The apparatus disclosed in Fig. 10, in which the insulating members 34 have been removed, will function properly under all normal conditions. To further prevent any outside rays of light from reaching the sight opening 18 in the container 15, as might happen under abnormal conditions, special plates 126, 127 and 128 have been provided in which the central flanges 132 have been extended outwardly at an angle and overhang each other, as shown in Fig. 11.

It will be noted by an inspection of Fig. 11 that although the flanges 131 overhang each other, there is no contact between them, thereby providing a continuous passage for induced air currents up through the apparatus and across the transparent members 44 and 43. This type of construction is desirable in some marine installations.

While the above description has dealt with the invention in specific connection with flame failure in furnaces and the like, it is to be understood that it may equally apply to other uses of a similar nature such as smoke control, densitometers or other apparatus in which light-sensitive equipment is used, within wide limits within the spirit of the appended claims.

Having thus described the present invention, what is claimed as new is:

1. A light-restricting container for housing a light-sensitive member comprising, heat-radiation members spaced apart and away from said container, supporting means for said container, means for circulating air between said radiation members and a heat-absorbing filter mounted between and in close proximity to said radiation members.

2. A light-restricting container for housing a light-sensitive member comprising, heat-radiation members spaced apart and away from said container, supporting means for said container, means for circulating air between said radiation members, a heat-absorbing filter mounted between and in close proximity to said radiation members, a transparent member located between said radiation members, and means for admitting a controlled amount of air across one side of said transparent member.

3. A housing apparatus comprising, a container housing a light-sensitive member, a sight opening located in one side of said container adjacent said light-sensitive member, heat-radiating plates spaced apart and away from said container and having apertures aligned with said sight opening, supporting means for said container, a shutter member pivoted on said supporting means between a pair of said heat-radiating plates, a heat-absorbing filter mounted in said shutter and normally aligned with said apertures, a second shutter member pivoted on said supporting means between a second pair of said heat-radiating plates, a transparent member mounted in said second shutter and normally aligned with said apertures, and an air inlet provided on one side of said second shutter for the purpose of allowing air to flow across one side of said transparent member.

4. A housing apparatus comprising a container housing a light-sensitive member, a sight opening located in one side of said container adjacent

5.

said light-sensitive member, heat-radiating plates spaced apart and away from said container and having apertures aligned with said sight opening, supporting means for said container, a shutter member pivoted on said supporting means between a pair of said heat-radiating plates, a heat-absorbing filter mounted in said shutter and normally aligned with said apertures, a second shutter member pivoted on said supporting means between a second pair of said heat-radiating plates, a transparent member mounted in said second shutter and normally aligned with said apertures, and means for locking said shutters in their normal position.

15.

5. Apparatus in accordance with claim 4 wherein said locking means comprises a pair of screws captive in one of said plates and threadably engaged with said shutters.

20.

6. Housing apparatus for a light-sensitive device comprising, a closed container having a sight opening adjacent said device; a plurality of plates having apertures aligned with said sight opening; a pipe flange coaxially aligned with said apertures; a plurality of bolts connecting said flange

25.

and said plates to said container; spacers encircling said bolts for spacing said plates apart and away from said container; a shutter pivoted on one of said bolts between one pair of said plates and having an opening, normally aligned with

30.

said apertures, wherein is mounted a heat-absorbing filter; and a second shutter, pivoted on one of said bolts between a second pair of said plates, and having an opening, normally aligned with said apertures, wherein is mounted a transparent member.

35.

7. Apparatus in accordance with claim 6 wherein said sight opening and said apertures are surrounded by lips having insulating collars mounted thereon.

40.

8. Apparatus in accordance with claim 6 wherein said sight opening and said apertures are surrounded by lips overlapping but spaced away from each other.

45.

9. Housing apparatus for a light-sensitive device comprising a closed container having a sight opening adjacent said device; a heat radiating plate having an aperture aligned with said opening; a pipe flange coaxially aligned with said aperture; a plurality of bolts connecting said flange and said plate to said container; spacers encircling said bolts for spacing said plate away from said container; a shutter pivoted on one of said bolts and a heat-absorbing filter mounted in close proximity to said plate.

55.
